[57] CLAIM

The ornamental design for a container for liquid fuel, as shown.

DESCRIPTION

FIG. 1 is a perspective view of a container for liquid fuel showing my new design;

FIG. 2 is a top plan view thereof;

FIG. 3 is an end elevational view thereof;

FIG. 4 is an end elevational view thereof opposite to that shown in FIG. 3;

FIG. 5 is a side elevational view thereof, the opposite side being a mirror image of that shown; and

FIG. 6 is a bottom plan view thereof.
